UNITED STATES PATENT OFFICE.

GEORGE L. BEERS, OF WILKINSBURG, PENNSYLVANIA, ASSIGNOR TO WESTINGHOUSE ELECTRIC & MANUFACTURING COMPANY, A CORPORATION OF PENNSYLVANIA.

SUPERHETERODYNE RADIO SYSTEM.

Application filed February 18, 1925. Serial No. 10,004.

My invention relates to radio receiving apparatus and particularly to such apparatus as employs the superheterodyne principle.

An object of my invention is to provide a 5 radio receiving apparatus of high selectivity with respect to two frequencies and in which means are embodied for removing one of the received frequencies.

Another object of my invention is to produce 10 a superheterodyne radio receiving apparatus embodying means for preventing response to a second frequency which may be heterodyned to the beat frequency.

Another object of my invention is to construct 15 a radio-frequency heterodyne radio receiving apparatus having a drain coil therein.

Another object of my invention is to construct 20 a superheterodyne radio receiving system having means for suppressing a second frequency to which the system is responsive.

Another object of my invention is to construct 25 a superheterodyne radio receiving system having a single tuning "hump."

In the operation of radio receiving apparatus 30 of the superheterodyne type, it has been found that there are two frequencies which may be simultaneously heterodyned to give the same beat frequency. The radio-receptor

35 system may be tuned to a given frequency and the local oscillator may be adjusted to the proper frequency to give a beat with the desired signal of a frequency to which the associated amplifier apparatus is responsive. Under 40 these conditions, the system is sensitive and is responsive to very weak signal-energy of the frequency to which the receptor is tuned. The rejector properties of the beat-frequency amplifiers cause other faint signals

45 to be attenuated to such an extent that they are not perceptible in connected signal translating apparatus. This attenuation is very marked because the radio receptor is tuned to a single frequency. Therefore, the system is very sensitive and very selective.

As is well known in the art, the superheterodyne radio receiving system produces at the receiving station a radio-frequency differing from the incoming signal frequency 50 and which is determined by the frequency to which the amplifier apparatus is tuned. The local oscillator may be set to generate at a frequency either higher or lower by the desired amount than the incoming signals.

If, in the desired application, the oscillator

is tuned to a frequency which is lower than that of the incoming signals, it is possible for other signals still lower in frequency by the same amount to react with the oscillation-generator frequency to produce the same 60 beat-frequency as the higher frequency signals. Under these conditions, the lower frequency signals will be received through the beat frequency amplifier apparatus.

If high power sending apparatus is in operation 65 near the receiving apparatus, it may force oscillations of low amplitude in the radio receptor. If these oscillations differ from the frequency of the local oscillator by the same amount that the desired faint signals differ, they will be heterodyned to the same frequency, which frequency is received and amplified by the associated apparatus 70 and made audible by the signal translator. Such interference is very objectionable, and is deceptive because of the fact that it disappears upon the change in the local oscillator 75 frequency and may cause the operator to mistakenly believe that he has received signals from the station which he desires to hear.

My invention provides means whereby 80 such interfering signals at a different frequency than the frequency to which the receptor is tuned, and which may be the second heterodyne frequency, are drained out of the system, or by-passed, before they reach the heterodyne oscillator and thereby are prevented from influencing the balance of the 85 system.

Other objects and structural details of my 90 invention will be apparent from the following description when read in connection with the accompanying drawings, wherein

Figure 1 is a diagrammatic representation 95 of circuits and apparatus embodying a preferred form of my invention; and

Fig. 2 is a diagrammatic representation of 100 circuits and apparatus embodying my invention in a manner in which it is twice applied.

In the drawings, a radio-receptor 1, which may be a loop-antenna, is tuned by a condenser 2 and connected to a triode 3 which amplifies received signals at the received frequency. This amplifier for signals at the incoming frequency is a desirable portion of the invention, but is not an essential part thereof. The amplified output of the repeater triode 3 is transferred by electromagnetic induction through transformer coils 4 and 5. An oscillation generator 6, of any desired form, 110

has a tuned circuit 7 which is positioned in electromagnetic inductive relation to the coil 5. Energy increments transferred to the coil 5 from the coils 7 and 4 combine to give beat phenomena which are resolved by the triode 8 and its associated circuit into a beat-note, corresponding with, and proportional to, the energy of the original incoming signal. This beat-note, which is modulated in accordance 10 with the original signal, is amplified by an amplifier 9, detected by a detector 11 and translated into sound by a telephone receiver 12.

A tuned resonant circuit, consisting of an 15 inductor 14 and a condenser 15, is connected across the terminals of the receptor 1 in parallel with the tuning condenser 2. The condenser 15 is adjustable and the inductor and condenser together constitute a series resonant circuit having a very low impedance to the frequency to which it is tuned and a very 20 high impedance to all other frequencies.

The system then operates in the following manner. Signals are received upon receptor 25 1, which is tuned by condenser 2 to a chosen frequency. These signals are then impressed upon the triode 3 and amplified thereby. The series-resonant circuit consisting of coil 14 and condenser 15 is tuned to another frequency and, therefore, does not by-pass a perceptible amount of the desired incoming signal-energy from the amplifier 3. The output 30 from the amplifier 3 is then heterodyned, amplified and detected in the usual manner.

In the presence of a powerful nearby station, the operator of the receiving apparatus 35 may have occasion to attempt to receive signals at a frequency which requires the local receiver oscillator to generate oscillation at a frequency which will simultaneously heterodyne oscillations of the frequency of the 40 nearby transmitting station to the same beat frequency as the desired signals. Thus the near-by station produces a troublesome interference. Under these conditions, the series 45 resonant circuit is tuned to the frequency of the nearby interfering station, whereupon it by-passes the oscillations in receptor 1 of the undesired frequency from the local sending 50 station and prevents most of their effect upon the triode 3.

Unless the nearby station is extremely close, or of tremendous power, the single by-pass circuit will serve to remove so nearly all 55 of the interfering energy that only an immaterial amount is conveyed through the heterodyne system and amplifier to the receivers.

Under extreme conditions of interference, however, a single drain coil may be insuffi-

cient and a second drain coil may be provided 60 as shown in Fig. 2, wherein an inductor 16 and a condenser 17 are connected across the terminals of the grid-coil 5 of the beat-resolving detector 8. The addition of the inductor 16 and condenser 17 will remove the 65 most troublesome interference.

If but a single station produces interference, the parallel resonant circuit may be tuned to the frequency of that station and may remain continuously adjusted to that 70 frequency. If, however, a plurality of stations are causing interference, the effect of all may be removed by interconnecting condenser 15 and condenser 2 as shown in Fig. 2 75 in such way that the frequency of the series resonant circuit is at all times such as to drain off the frequency which is such as to be heterodyned to the same frequency as the desired signal. By employing this mechanical interconnection, there is but one so-called "tuning 80 hump" in the resonant system and the system as a whole is responsive to but a single frequency and is not responsive to other frequencies of whatever amplitude.

While I have shown but two embodiments 85 of my invention in the accompanying drawing, it is capable of various other changes and modifications therefrom without departing from the spirit thereof, and it is desired, therefore, that only such limitations shall be 90 placed thereon as are imposed by the prior art or indicated in the appended claims.

I claim as my invention:

1. A signal-responsive system comprising an input circuit including tuning means, an 95 oscillator circuit, a filter circuit including tuning means, means for mechanically coupling said tuning means for simultaneous adjustment to maintain the filter circuit so tuned as to filter out an undesired frequency 100 which differs from the frequency of the oscillator circuit by an amount equal to one half the difference between said undesired frequency and the frequency of said input circuit.

2. A radio receiving system comprising means for tuning its input, adjustable means for reducing a desired signal frequency simultaneously with a materially different interfering signal frequency to the same lower 110 frequency, variable means for removing the undesired frequency and means common to said first named and said last named means for varying them simultaneously.

In testimony whereof, I have hereunto subscribed my name this 14th day of February 115 1925.

GEORGE L. BEERS.
